UNITED STATES PATENT OFFICE.

WILLIAM H. MUSSEY AND WILLIAM R. PETERSON, OF CHICAGO, ILLINOIS, ASSIGNORS TO FULLMAN CAR & MANUFACTURING CORPORATION, OF CHICAGO, ILLINOIS, A CORPORATION OF ILLINOIS.

PLATFORM AND GATE ASSEMBLY.

Application filed October 19, 1925. Serial No. 63,484.

The invention relates to mechanism for use on platforms of railway passenger cars and particularly on the platforms of observation cars which are usually enclosed by 5 a railing made up of horizontally swinging side and end gates with fixed portions between the gates.

The principal object of the invention is to provide means fixed to the body of the car 10 in the plane of the platform railing side gates and above each trap door in position to engage the respective side gates and trap doors, the devices comprising said means being mounted upon a support common to 15 all of them, all of the assembled parts being held by the support in fixed operating relation to each other and the platform gates and trap doors.

A further object is to so interlock the 20 platform railing side gates with a holding device rigidly secured to the car that the gate proper will operate to connect the holding devices on the car body to the fixed portions of the railing.

25 The foregoing and other objects are attained by the mechanism illustrated in the accompanying drawings, in which—

Fig. 1 is a plan of a portion of an observation car platform showing the relation of 30 trap door and gate to the holding device on the car body;

Fig. 2 is a vertical section through the platform taken on line 2—2 of Fig. 1 looking in the direction indicated by the arrows;

35 Fig. 3 is a broken front elevational view of the holding device on an enlarged scale showing the relation of the gate interlocking portion and latch to the trap door catch and grab handle;

40 Fig. 4 is a side-elevational view thereof;

Fig. 5 is a bottom plan of the connecting shoe of the holding devices;

Fig. 6 is a horizontal sectional view taken 45 on line 6—6 of Fig. 3 looking in the direction indicated by the arrows; and

Fig. 7 is a horizontal sectional view through the connecting cap piece of the holding devices taken on line 7—7 of Fig. 3 looking in the direction indicated by the 50 arrows.

In said drawings, 10 indicates the body of a car equipped with the invention, 11 the platform, and 12 the railing enclosing the platform. The railing is made up of the

fixed portions 13 secured to pillars 14 supported in buffer sill 15 of the car under-frame and the horizontally swinging side gate portions 16 pivotally secured by hinges 17 to fixed portions 13 of the railing. Trap doors 18 are pivotally mounted at right angles to the gates on brackets 19 secured to the end sill 20 of the car underframe in position to be engaged by the catch 25 when raised to the open position indicated in dotted lines in Fig. 2 as will hereinafter 65 appear. The trap doors are held in their closed position at the platform level by means of any approved form of lock 21, such as illustrated in the drawing containing the usual sliding bolt 22 normally held above 70 the free edge of the trap door 18 with bolt retracting shaft 23 extending upwardly therefrom and fitted with operating handle 24 in position to be conveniently reached by 75 the operator.

The side gate 16, constituting the movable portion of the platform railing, swings in a horizontal plane above the trap door 18. When in its closed position the gate is held parallel to the outer edge of the trap door 80 with its hinge portion 17 at the free edge of the trap door and with the free edge of the gate at the pivoted side of the trap door. Thus positioned the gate will lie in the path of movement of the trap door 18 to limit 85 any premature rising of the trap door resulting from the failure or unauthorized manipulation of the trap door lock 21, further upward movement of the trap door being checked upon contact thereof with lower rail 90 26 of the gate 16. It will be obvious that until the gate is swung inwardly beyond the free edge of the trap door the trap door will be held down to prevent accidental injury to persons occupying the platform. 95

To insure stability in the platform railing as a whole, the gates 16 are interlocked with the body of the car through the medium of holding devices 27 constituting the connecting cap piece of the group, and the connecting shoe piece 28.

The cap piece 27 is provided with securing flanges 29 and 30 shaped to the contour of the contiguous body portion of the car and perforated as at 31 to receive a plurality of machine screws or the like for attaching same to the car body. The cap piece 27 is also equipped with a body portion shaped

to provide a coupling 33 designed to interlock with a complementary coupling 34 on gate 16. The couplings 33 and 34 are held in intimate interlocking engagement by means of a retaining latch 35 pivotally mounted at 36 on cap piece 27 and adapted to engage a wedging face 37 on gate coupling 34. Latch 35 is normally held against face 37 by means of spring 38 having its opposite ends seated in pockets 39 and 40 of the cap piece and latch respectively, as best shown in Fig. 7 of the drawings.

Forming part of the cap piece 27 is a hand-hold portion 41 projecting laterally from the cap piece and downwardly with its terminal portion 42 in position to interlock with the upper end of the main hand-hold portion 43 as indicated in Fig. 4 of the drawings. Interlocking with the lower end 20 of hand-hold 43 is a similar hand-hold extension 44 projecting laterally and upwardly from the shoe piece 28. The shoe piece carries a flange 45 which, like flanges 30 and 31 of cap piece 27, is provided with countersunk holes 46 to receive a sufficient number of machine screws for the proper fastening of the shoe to the car body. The shoe piece is notched out as at 47 to receive tongue 48 on the lower rail 26 of gate 16 30 as shown in Fig. 2.

The cap and shoe pieces 27-28 are connected by a post section 49 having at its upper end a swelled pocket portion 50 containing the plunger mechanism of trap door catch 25. The plunger mechanism consists of the plunger rod 51 seated upon spring 52 and fitted with head 53. Plunger pocket 50 is covered and the mechanism protected by lid plate 54 secured to the post 49 40 preferably by screws 55, the plate functioning also as a wear plate for the free edge of the trap door 18 when raised to open position indicated in dotted lines in Fig. 2. The connecting post 49 may also be provided 45 with openings 56 to receive additional fastening means should that be found necessary.

The gate 16 is released by grasping handle 57 of retaining latch 35 and pressing the 50 latch inwardly against the spring 38 and past the wedging face 37 on the gate until the latch assumes the position indicated in dotted lines in Fig. 7 whereupon the gate will be free to swing past the latch to its 55 open position beyond the free edge of the trap door. Bolt 22 of trap door lock 21 is then retracted and the trap door raised to its open position against wear plate 54 on the plunger mechanism pocket 50 in which 60 position the trap door will be held by latch 25 engaging the underface of the trap door at latch opening 58.

To close the gate the trap door is released from its open latched position by depressing plunger rod 51 against spring 52 thereby

disengaging latch 25 from the trap door. The trap door is forced to its closed position in the platform and held there by lock bolt 22, after which the gate 16 is swung to closed position past the retractile latch 35 whereupon the coupling portion 34 on the gate will engage the coupling 33 on cap piece 27 whereupon latch 35 will engage wedging face 37 on the gate and hold same closed.

It will be noted that there has been provided a construction in which the holding devices for the platform railing are held in grouped relation and applied to the car as a unit, thereby facilitating the assembling 80 of car body and platform elements and insuring greater accuracy in the operating relation of the several parts.

What we claim is:—

1. In a platform and gate assembly, the 85 combination comprising a platform railing having horizontally swinging side gate portions, platform trap doors pivotally mounted on the car body at right angles to said gates, and connected holding devices secured to the car body at the free ends of said gate portions and in assembled relation to each other and said gates and trap doors.

2. In a platform and gate assembly, a 90 platform railing having horizontally swinging side gate portions, connected holding devices connecting said gates to the car body, coupling portions on said gates adapted for interlocking engagement with said holding devices, and gate latching means.

3. In a platform and gate assembly, a 95 platform railing having swinging side gate portions, holding devices connecting said gates to the car body, complementary couplings on said gates and devices, and gate latching means on said holding devices adapted to hold said couplings in interlocking engagement.

4. In a railway car platform and gate assembly comprising a platform railing having pivoted side gate portions, holding devices connecting said gates to the car body and including upper and lower securing pieces, and bars connecting said pieces, one of said bars constituting a hand-hold in said 110 assembly.

5. In a platform and gate assembly, the 115 combination comprising a platform railing having horizontally swinging connecting side gate portions, trap doors pivoted to the car body adjacent the free ends of said gates, connected holding devices securing said gates to the car body, coupling portions formed on said gates and holding devices, and locking means on said devices for holding said trap doors raised.

6. In a platform and gate assembly, the 120 combination comprising a platform railing having horizontally swinging side gate portions, platform trap doors pivotally mounted

on the car body adjacent the free ends of said gates, holding devices at the free ends of said gates, and locking means on said devices for holding said trap doors raised.

5. 7. In a platform and gate assembly, the combination comprising horizontally swinging side gate portions, trap doors pivotally mounted on the car body at right angles to and adjacent the free ends of said gates,

holding devices connecting said gates to the 10 car body and including upper and lower securing pieces, bars connecting said pieces, and trap door latching mechanism on one of said bars.

In witness whereof we have hereunto set 15 our hands this 14th day of October, 1925.

WILLIAM H. MUSSEY.

WILLIAM R. PETERSON.
